UNITED STATES PATENT OFFICE.

JOHN BURRY, OF RIDGEFIELD PARK, NEW JERSEY; MARIE BURRY EXECUTRIX OF SAID
JOHN BURRY, DECEASED.

PRINTING-TELEGRAPH RECEIVER.

No. 905,126.

Specification of Letters Patent.

Patented Nov. 24, 1908.

Application filed March 30, 1906. Serial No. 308,954.

To all whom it may concern:

Be it known that I, JOHN BURRY, a citizen of the United States, residing at Ridgefield Park, in the county of Bergen and State of New Jersey, have invented certain new and useful Improvements in Printing-Telegraph Receivers, of which the following is a specification, reference being had to the drawings accompanying and forming part of the same.

My invention relates to receiving devices for printing telegraph systems, and has for its object to provide a receiving apparatus of the utmost simplicity of construction and certainty of operation, so that the same may be used by unskilled persons, and in places where the apparatus will be subjected to severe vibrations or shocks.

Attempts have been made in the army and navy to utilize printing telegraphs to supply to gunners the data found by a distant range finder, but it has been found that the systems commonly in use are too delicate in construction to withstand the severe usage to which the apparatus is unavoidably subjected. The receiver must of course be located near the gun which the gunners are serving, and consequently the concussion and vibration produced by the discharge of the gun are communicated to the receiver, resulting in frequent derangement of the same.

My object has therefore been to provide a receiving apparatus which shall be able to withstand such usage indefinitely and to operate with certainty and precision at all times.

The most important feature of my invention resides in the employment of a type plate, as distinguished from the usual wheel or cylinder, which plate is by means of suitable magnets under the control of the distant transmitter shifted laterally and longitudinally to bring any selected character to the impression point or printing position. In the preferred embodiment of the invention the type plate is carried at the end of a bar or lever which is capable of oscillation on either of two fulcrums at will, and also of being shifted laterally and longitudinally. The use of two fulcrums gives two oscillations, and the lateral shifting of the lever gives a third movement, from the normal or initial position of the type plate. In this way any of four longitudinal rows of type on the plate may be selected for printing. Between the two fulcrums a second arm or

lever is pivoted to the first, substantially at right angles thereto, this second lever being also capable of oscillation on two fulcrums and of being shifted longitudinally and transversely. These movements of the second lever shift the first arm, and hence the type plate, longitudinally, and enable any transverse row on the plate to be selected for printing. In this way any one of sixteen characters on the plate may be printed at will, and it is clear that by providing additional movements for the levers additional characters may be used. The principle of the invention, however, is amply illustrated in the present form, and sixteen characters are all that are needed for the purpose above mentioned.

In order to effect the movements of the levers I employ four electromagnets, preferably, though not necessarily, in four independent circuits. These magnets may be energized singly or in groups, or not energized at all, giving, by simple permutation, the sixteen different positions of the type plate. In the preferred construction the magnet armatures carry the fulcrums of the levers, so that when one fulcrum or pivot is acting as such, another serves as the means for oscillating the lever, while energization of both magnets on the same lever causes the latter to be shifted bodily in a transverse direction.

The impressions are made preferably on a tape, drawn longitudinally over the printing point by suitable mechanism. In the form herein illustrated the printing and the feed of the tape are effected by the agency of a fifth magnet, in a fifth circuit.

It will be apparent to those skilled in the art that the scheme above outlined may be embodied in widely differing forms and that the same may be employed for a great variety of purposes.

A simple and convenient embodiment, designed more particularly for the artillery service above mentioned, is illustrated in the annexed drawings, in which—

Figure 1 is a top plan view of the receiver. Fig. 2 is a section on line II.—II., of Fig. 1. Fig. 3 is an end elevation. Fig. 4 is a detail plan view of the type plate. Fig. 5 is a detail sectional view of the printing devices showing the type plate, the ink ribbon, the tape, and the platen. Figs. 6 to 12 are diagrammatic views illustrating the

adjustment of the type plate to bring selected characters to the printing point. Fig. 13 is a simple diagram showing the wiring of the system.

5 The various parts of the apparatus are conveniently mounted on a base plate 1. Rising therefrom are three standards or posts 2, 3, 4. Supported on these standards is a table 5 and a right angled extension 10 thereof, 6.

Resting loosely on the table 5 is a flat lever 7, provided with longitudinal slots 8, 9, one at the end and the other at about the center of the lever. Directly under these 15 slots, in the table 5, are transverse slots 10, 11, and projecting upwardly through the slots are pins 12, 13, carried by armature levers hereinafter more fully described.

Pivoted to the lever 7, at right angles 20 thereto and midway between the slots therein, is a second lever, 15. The latter has longitudinal slots 16, 17, arranged as those in the first lever, over transverse slots 18, 19 in the extension 6. Pins 20, 21 project upwardly through these slots, as in the former case.

Carried at the forward end of the lever or arm 7 is a type plate 22, on which, in the present instance, are sixteen characters, arranged in four straight longitudinal rows and four curved or arc-shaped transverse rows. The type plate and the arrangement of the characters thereon are clearly shown in Figs. 1 and 4, the longitudinal rows, that 35 is, the rows which extend longitudinally of the lever 7, being designated by *a*, *b*, *c*, *d*, respectively, and the transverse rows by *a'*, *b'*, *c'*, *d'*, respectively.

Immediately below the type plate, and 40 movable upward through an opening in the end of the table 5, is a vertical pin or bar 23, (see Fig. 5), adapted by its vertical movement to carry the type plate upward against a paper strip or tape 24. Under the 45 latter is an inked tape and ribbon 25, and above the ribbon is a platen 26, having a flat boss 27 directly over the pin or bar 23. Consequently when the latter rises the paper and inked ribbon will be struck against the 50 platen and an impression on the paper will be made of whatever type or character is at the impression point, that is to say, directly over the bar 23 and under the boss 27. With the ink ribbon running between the 55 impression tape and the platen, the latter soon acquires a thick, rounded or convex layer or coating of ink, the convexity of which confines the impression to the central portion of the type, leaving the outer portions untouched, and thus producing a confusing or even illegible imprint. But with the ribbon running between the tape and the type plate, the platen never comes in contact with the ribbon, and hence is kept clean.

However, arranging the ribbon below the 65 tape causes the impressions to be made on the under or unexposed side of the tape, as will be readily understood; but it is desirable, particularly in the artillery service mentioned, that the impressions be visible 70 as fast as printed. I secure this result by using a tape which is at least translucent, preferably as nearly transparent as possible, so that the impressions, though made on the unexposed side of the same, are yet clearly 75 readable through the tape.

As previously stated, the type plate is shifted longitudinally and transversely to bring any desired letter to the impression point. This shifting of the plate is effected 80 as follows, referring to Figs. 1 and 6-12.

The initial position of the plate is shown in Figs. 1 and 6, with the dash, which is in rows *b* and *b'*, at the impression point. The pins 12 and 13, extending through slots 11, 85 9, and 10, 8, respectively, constitute fulcrums, normally fixed but movable simultaneously, and independently. If the magnet 28, hereinafter more fully described, be energized, it will draw the pin 13 over, as 90 in Fig. 7, throwing the type plate to the right, until the pin 13 strikes the left end of slot 11, and bringing row *a* to the impression point above the bar or plunger 23. In this movement the pin 12 acts as the fixed fulcrum, while the other, 13, swings the lever. If now magnet 29 be energized, or both magnets simultaneously, both pins will be drawn over and the lever 7 will be shifted bodily to the left, such movement being permitted 95 by the slots 16, 17, in the arm 15, bringing row *c* to the impression point, as in Fig. 8. If only magnet 29 be energized the pin 13 will act as the fulcrum and pin 12 will draw the lever to the left, and since the fulcrum 100 is now at the end of the lever the swing of the latter will be longer, and will bring row *d* to the impression point, as in Fig. 9. In this way any of the longitudinal rows *a*, *b*, *c*, *d* may be brought to the printing position. 105 As already stated, row *b'*, of the transverse rows, is normally at the impression point. If now magnet 30, Fig. 10, be energized, pin 20 will draw the outer end of the lever down, on pin 21 as the fulcrum, and retract lever 110 7 and with it the type plate, bringing transverse type-row *a'* over the bar 23. If magnets 30 and 31 are both energized the arm 15 will be shifted bodily downward, bringing row *c'* to the impression point, as in Fig. 11. Energizing magnet 31 alone will give the arm 15 a longer sweep, and bring row *d'* over the printing bar 23. Any of these 115 movements of the arm 15 may be combined with any movement of the lever 7, so that 120 any character on the plate can be brought to the impression point, as will be readily understood. The movement of the type 125

plate is limited by the pins striking the ends of the slots in the table 5 and extension 6, so that the position of the plate is always accurately determined.

5 As previously stated, the pins 12, 13, 20, 21 are carried by armature levers, indicated by 32, 33, 34, 35, respectively, arranged to be actuated by the magnets 29, 28, 30, 31, respectively. These magnets are mounted 10 on the base 1, and their armature levers are pivoted in front of them. The armatures are normally retracted, to the position of Fig. 1, by springs 36, 37, 38, 39, which engage L-shaped arms 40, 41, 42, 42, connected 15 with their respective armatures by links 44, 45, 46, 47. It will be seen that by this method each armature is yieldingly held in its normal position with some degree of firmness, so as not to be disturbed by the 20 other magnets. Each armature, however, yields to its own magnet, and by reason of the arm connecting it with its spring the force of the latter immediately diminishes. It is therefore necessary that magnets exert 25 their maximum force as the armatures start, and to secure this result the pole pieces of the magnets are extended so that the armatures move between them, as clearly shown, for example, in Fig. 1. By this construction 30 each armature offers maximum resistance to movement by other magnets than its own, yet moves with diminishing resistance when its own magnet is energized. The operation of the machine is thus made positive and 35 sure at all times.

To effect the printing a vertical magnet 48 is provided; on the end of whose armature lever 49 the printing pin or bar 23 is mounted. The armature 49 is pivoted at 40 the top of a standard 50, so that energization of the magnet will raise the printing pin against the tension of the spring 51.

The tape 24, on which the impressions are made is carried in a roll on a reel 52, 45 mounted on the post 4, and passes upwardly over and in contact with a scape wheel 53, carried by arms 54 depending from the table 5. The scape wheel is faced on its periphery with a friction material, such as soft rubber, 50 so that the pull of the tape will rotate the wheel. Projecting laterally from the wheel, near its periphery, are equally spaced pins or teeth, 55, the spaces between the teeth being equal to the desired spaces between 55 successive impressions on the tape. Projecting from the lever 49 at one side of the scape wheel is an arm 56, having at its end a notch 57, the outer side of which is formed by an upwardly projecting lug or stop 58. 60 Extending forwardly and laterally from the lever 49, and into the notch 56, is a spring finger 59, the end of which is adapted to engage the pins or teeth 55. Extending toward the scape wheel from the base of the

stop 58 is a stud 60, leaving a space below 65 the finger 59 wide enough for the teeth 55 to pass. The operation of this escapement is as follows: The tape, under constant tension, keeps the parts normally in the position shown in Figs. 2 and 3, the armature 49 70 having retracted the printing pin or hammer 23. When the armature is raised to produce an impression, the spring finger is lifted above the tooth engaged by it, and the lug 60 is brought into engagement with the 75 tooth, while the spring finger lies over toward the other side of its notch against the next tooth. The continued upward movement of the armature carries the printing bar against the type plate and takes an impression therefrom. On return of the armature the lug 60 is carried down out of engagement with the tooth resting against it, and said tooth escapes between the lug and the spring finger, which latter is at the same 80 time carried back to its initial position by the tooth which it engaged after it had been released by the first tooth. By this arrangement the feed occurs after the impression is taken, and the tape is therefore held stationary until the impression is made and the 85 type plate withdrawn slightly.

For the purpose of keeping the tape in firm engagement with the scape wheel a presser roller 61 is provided, carried in a 95 yoke 62 which is pivoted at its rear end to a stud 63 on the plate 26. The yoke may thus be swung upward, carrying the presser roll away from the tape and the scape wheel, but is held normally in its operative position by a spring 64. The ink ribbon is preferably 100 in the form of an endless belt, passing over a small drum 65 mounted on the table 5 and a second drum 66 carried by a spring arm 67 on the other side of the base 1. The 105 spring arm 67 keeps the ribbon belt under slight tension. On the end of the escapement shaft, under the drum 65, is a pulley 68, connected by a belt 69 with the drum 65, so that the latter will be rotated with the 110 scape wheel and thus cause the ribbon to travel and present a fresh surface each time an impression is made. From the scape wheel and presser roll the tape passes above the table 5 to a small roller 70, then downward over a roller 71 at right angles to the other, and is then wound on a reel 72. The latter is rigidly mounted on a shaft 73 which extends to a point in the rear of the armature lever 49, where it carries a revolubly 115 mounted ratchet wheel 74. On the shaft, and frictionally engaging the same and the ratchet is a coil spring 75, so that rotation of the ratchet wheel will wind up the spring and cause the reel to be rotated with yielding force. The ratchet is rotated by a pawl 76, depending from the armature 49, whenever the armature is drawn down to print a 120 125

character. In this way the spring is kept constantly under sufficient tension to draw the tape off the reel 52. Reverse movement of the ratchet is prevented by a holding pawl 77.

The wiring of the system is illustrated diagrammatically in Fig. 13. In this figure 28, 29, 30, 31, 48 represent the same magnets as in the other figures, and it will be seen 10 that each magnet is in an independent circuit, controlled by its own key. It is clear, however, that by the use of suitable controlling devices the various magnets could be operated by three, two, or even one circuit. 15 For example, in my co-pending application Serial No. 233,484, now Patent No. 785,410, issued December 31, 1907, I have described a system in which four selecting magnets and a printing magnet are operated by two 20 line circuits. Any convenient transmitter can be used to operate the transmission keys, as for example a transmitter of the type shown in my co-pending application Serial No. 217,570, now Patent No. 854,401, issued 25 May 21, 1907.

The operation of the receiver having been described in connection with the mechanism, further explanation of the same is deemed unnecessary.

30 It is clear that numerous modifications may be made in the apparatus illustrated without departure from the proper scope of the invention.

35 The invention is herein described, for convenience, as part of a printing telegraph system, but it is not confined to the actual printing of characters, since it may be used to give intelligible signals by the mere movement of the type plate or a member corresponding 40 thereto, according to a prearranged code, or in other ways.

What I claim is:

45 1. In a printing telegraph receiver, the combination of a lever, a type plate carried thereby, a plurality of fulcrums for the lever, and electrically actuated means for oscillating the lever on any of the fulcrums, as set forth.

50 2. In a printing telegraph receiver, the combination of a lever, a type plate carried thereby, means for oscillating the lever, and means for shifting the lever bodily in a longitudinal and in a transverse direction, as set forth.

55 3. In a printing telegraph receiver, the combination of a lever, a type plate carried thereby, means for swinging the lever, an arm extending laterally from the lever, and means for swinging the arm to shift the lever longitudinally, as set forth.

60 4. In a printing telegraph receiver, the combination of a lever having two longitudinal slots, a type plate carried by the lever, pins projecting through the slots, armatures carrying the pins, and electromagnets ar-

ranged to actuate the armatures transversely to the lever, as set forth.

5. In a printing telegraph receiver, the combination of a lever having longitudinal slots, a type plate carried by the lever, a laterally extending arm or lever pivoted to the first lever and having longitudinal slots, pins projecting through the slots, armatures carrying the pins, and electromagnets arranged to actuate the armatures transversely to their respective levers, as set forth. 70

6. In a printing telegraph receiver, the combination of a type plate, a lever carrying the same, an arm pivoted to the lever and extending laterally therefrom, electromagnetic means for swinging the arm and the lever and for shifting them transversely and longitudinally, and means for taking impressions from the type plate, as set forth. 80

7. In a printing telegraph receiver, the combination of a type plate, a lever carrying the same, a plurality of fulcrums for the lever, armatures carrying the fulcrums, electromagnets to actuate the armatures, and means for yieldingly holding the armatures with maximum resistance at the beginning of their stroke, as set forth. 85

8. In a printing telegraph receiver, the combination of a type plate, a lever carrying the same, a plurality of fulcrums for the lever, armatures carrying the fulcrums, means for yieldingly holding the armatures with maximum resistance at the beginning of their stroke, and electromagnets for actuating the armatures, adapted to exert their maximum power on the armatures when the latter are at the beginning of their stroke, as set forth. 95

9. In a printing telegraph receiver, the combination of a table having a lateral extension, a lever on the table, an arm connected to the lever and extending over the said extension of the table, pins extending through the table and extension and working in slots in the lever and arm, magnets 105 for actuating the pins singly or in groups to adjust the lever longitudinally and transversely, a type plate carried by the lever, and means for taking impressions from the type plate, as set forth. 110

10. In a printing telegraph receiver, the combination of a lever, a type plate carried thereby, means for adjusting the lever laterally and longitudinally, means for carrying an impression tape past the type plate, 120 means for taking impressions from the type plate on the tape, and an escapement actuated by the impression taking means for controlling the movement of the tape, as set forth. 115
